UNITED STATES PATENT OFFICE.

CHARLES W. VAN ALSTINE, OF NEWTON, MASSACHUSETTS.

SELF-CLOSING TOBACCO-BAG.

SPECIFICATION forming part of Letters Patent No. 400,020, dated March 19, 1889.

Application filed August 28, 1888. Serial No. 283,987. (No model.)

To all whom it may concern:

Be it known that I, CHARLES W. VAN ALSTINE, a citizen of the United States, residing at Newton, in the county of Middlesex and

5 State of Massachusetts, have invented certain new and useful Improvements in Self-Closing Tobacco-Bags; and I do hereby declare the following to be a full, clear, and exact description of the invention, such as will enable others skilled in the art to which it appertains to make and use the same.

This invention relates to bags which are provided with means for closing their mouths or open ends automatically when released by 15 the persons or appliances which hold them open during the operation of filling or getting at the contents.

The object of my improvement is to hold the mouth of the bag flat and smooth when 20 closed, and to provide a durable closing device which will effectually prevent the escape of any part of the contents when left free to act and may be easily withdrawn at will, though holding its position securely against 25 accidental displacement. To this end I employ a spring of considerable strength acting in two opposite directions, and thus drawing the sides of the mouth of the bag tightly together, so that they will be smooth and flat.

30 I provide this spring with a central coil from which two arms, the elongated ends of said coil, extend obliquely upward and outward, being shaped at the ends to hold the mouth of the bag detachably but firmly.

35 In the accompanying drawings, Figure 1 represents a bag provided with my spring for automatically closing it, the latter being chiefly shown in dotted lines within said bag; and Fig. 2 represents a perspective view of 40 said spring detached.

45 A designates the bag; B, the central coil of the spring; C, the arms extending obliquely upward and outward on each side from the ends of said coil, which exerts through them its resiliency in two opposite directions, and D, the hooks formed on the ends of said arms, each hook first curving inward to form a rounded shoulder, d, then outward and down to d', nearly meeting said shoulder, and then 50 slightly outward, in order that the extremity d' may not be in the way of the bag when the

spring is inserted in the mouth of the latter. The parts or features B C D are preferably formed from one piece of spring-wire, left integral.

55

The spring is applied to the bag by spreading the mouth of the latter and passing the coil B and arms C down within it, slightly compressing said arms until the fabric of the mouth of the bag at two opposite points passes 60 between the shoulders d and the contiguous parts d' of the tips of the hooks D, a slight amount of force being necessary to force the edges through between these parts to the open spaces in the upper parts of said hooks, the 65 position shown in Fig. 1. The outward pressure of the arms C and the shape of the hooks B now combine to hold the mouth of the bag against separation from the spring, and this pressure also draws together the sides of the 70 said mouth intervening between the two points at which it is applied. By pulling these sides apart and compressing the spring, or by the former only, the mouth may be readily opened for the purpose of filling the bag or inspect- 75 ing or withdrawing any part of the contents. As soon as released the spring will close it again, preventing the escape of any part of the contents. Ordinarily, after filling the bag, the spring is withdrawn by simply pull- 80 ing it upward. The upper parts of the hooks B make good handles for this purpose. The same spring may be used with any number of bags successively; but I may also provide each bag with one, the springs being so flat 85 that a great number of these self-closing bags may be piled on each other for storage or transportation or while temporarily awaiting use. The mouth of the bag is not pursed or crumpled in any way which would interfere 90 with such piling or packing. The spring is subjected to but little strain, is practically unaffected by wear, and will last for a long time with no perceptible diminution of efficiency.

Having thus described my invention, what I 95 claim as new, and desire to secure by Letters Patent, is—

1. A bag provided with a spring, consisting of coil B, arms C, and terminal hooks for said arms, the spring being arranged within the 100 mouth of the bag, for the purpose of closing the same automatically, and the hooks fitting

detachably over the edge of said mouth, as set forth.

2. A spring provided with the central coil, B, the arms C, extending upward and outward, 5 and the hooks D, having shoulders d , curved proximate parts d' , and outwardly-turned tips d'' , all specially adapted, as described, to hold the mouth of a bag together and allow the convenient attachment and detachment of said

spring to and from said bag, for the purposes set forth.

In testimony whereof I affix my signature in presence of two witnesses.

CHARLES W. VAN ALSTINE.
